United States Patent Office

Des. 198,155
Patented May 12, 1964

198,155

ELASTIC FABRIC

Herma Wiedle Dozier, 6609 Olive Blvd.,
St. Louis 5, Mo.

Filed Jan. 8, 1960, Ser. No. 58,961

Term of patent 14 years

(Cl. D3—32)

The figure on the drawing is a plan view of an elastic fabric showing my new design.

The present application is a continuation-in-part of application Serial No. D-49,090, filed January 2, 1958 and now abandoned.

I claim:

The ornamental design for an elastic fabric, substantially as shown and described.
